UNITED STATES PATENT OFFICE.

WILLIAM M. CUMMISKEY, OF HONESDALE, PENNSYLVANIA, ASSIGNOR TO HOWARD F. GURNEY, OF NEW YORK, N. Y.

ELECTRIC ELEVATOR.

No. 909,872.

Specification of Letters Patent.

Patented Jan. 19, 1909.

Application filed June 5, 1908. Serial No. 436,824.

To all whom it may concern:

Be it known that I, WILLIAM M. CUMMISKEY, a citizen of the United States, and a resident of Honesdale, in the county of Wayne and State of Pennsylvania, United States of America, have invented certain new and useful Improvements in Electric Elevators, of which the following is a specification.

10 My invention relates to improvements in electric elevators and particularly to a novel connection of the electrical circuits used in the controllers for such apparatus, and its object is to increase the safety and efficiency of installations of this character.

15 I will describe my invention in the following specification and point out the novel features thereof in claims.

Referring to the drawings, Figure 1 is a diagrammatic representation of certain portions of an elevator apparatus and associated parts together with certain connected electrical circuits which are used in carrying out my invention. Fig. 2 is a side elevation of 20 a brake mechanism together with some of its associated parts illustrating a modification of certain wiring connections, and in Fig. 3 another modification of wiring is illustrated.

Like characters of reference designate corresponding parts in all of the figures.

30 In the drawings + and — designate mains from a suitable source of electrical supply which, after passing through a main-line switch 10, run to various parts of the apparatus through circuits which will be pointed out hereinafter.

35 20 is a starting switch which comprises a plurality of stationary contacts 21, 22, 23, 24, 25 and 26 and two movable contact plates 27 and 28. The latter are mounted upon but 40 insulated from a vertical movable rod 29 which is connected with the core 31 of an electromagnet or solenoid 30 by means of a rod 33. 32 designates the winding of this 45 solenoid.

34 is a piston affixed to the connecting rod 33. 35 is a closed cylinder surrounding this piston and arranged to form an air-cushion or dash-pot for controlling the rapidity of 50 movement of the piston 34 and its connected parts in both directions.

55 40 is a reversing switch which comprises stationary contacts 41, 42, 43, 44, 45, 46, 47 and 48 and movable contact plates 49 and 50 mounted upon but insulated from a vertical

rod 51 which is directly above the rod 29. A pendant 52 is pivoted to the lower end of the rod 51 and is normally in alinement with the rod 29. It is provided with a slot 53 into which a pin 54 projects. This pin is 60 on a rod 55, one end of which is attached to the core 56 of a solenoid, the winding of which is designated by the numeral 57. The other end of rod 55 supports an insulated contact plate 58 which is pressed against two 65 stationary contacts 60 and 61, by means of a spring 59. Whenever solenoid winding 57 is energized the contact plate 58 will be drawn back against stationary contacts 62 and 63 and at the same time the pendant 52 70 will be drawn back into the position shown in dotted lines and out of the path of movement of the rod 29.

64 designates the armature of an electric motor which, in any of the well-known 75 manners, is arranged to drive a hoisting mechanism and a car. The armature terminals of this motor are connected by conductors 65 and 66 with stationary contacts 42 and 44, respectively. The terminals of 80 the shunt field 67 of this armature are connected by conductors 68 and 69 with stationary contacts 25 and 24, respectively.

Below the solenoid 30 a brake 70 is shown. This comprises a brake-pulley 71 and a pair 85 of brake-shoes 72 mounted upon pivoted levers 73, the upper ends of which are connected together and to a rod 36 by means of a pair of toggle-levers 37. The rod 36 is affixed to the solenoid core 31 and the parts 90 are so arranged that when the solenoid 30 is energized and the core 31 raised thereby the pivoted levers 73 will be pushed apart and the brake-shoes released. When the solenoid is deenergized, the weight of its core 95 and its connected parts will force the pivoted levers 73 together and thereby apply the brake-shoes to the pulley 71 which is connected to some movable part of the elevator hoisting mechanism. 74 is a contact 100 plate mounted upon one of the brake-levers 73, and 75 and 76 are stationary contacts with which this contact plate coats.

80 is an automatic rheostat which is arranged to gradually cut a resistance 81 out 105 of the motor armature circuit. This rheostat comprises a pair of brushes 82 which bear upon and make contact with a metallic strip 83 and a plurality of stationary contacts 84. The resistance 81 is connected to 110

each one of the latter so that when the brushes 82 are moved up over the stationary contacts, the resistance is cut out in a plurality of steps. The brushes 82 are mounted upon a vertical rod 85 which depends from the core 86 of a solenoid, the winding of which is designated by 87. A piston 88 is attached to one end of the rod 85. This piston is within a closed cylinder 89 which may be filled with oil or other fluid, and is arranged to retard the upward movement of the brushes 82. A valve in the piston 88 allows the piston and its connected parts to move freely downward.

Above the solenoid 87 and in the path of movement of its core 86 is a switch 14 which is ordinarily resting against a contact 15. 16 is a resistance connected with this contact and with one of the terminals of the solenoid 87.

90 designates an elevator-car within which is a manually operated switch 91 which comprises a pivoted lever 92 and two stationary contacts 93 and 94. This lever may be moved into engagement with either one or the other of these contacts.

The above description is of the various parts of the apparatus which are connected together by a wiring system made up of a plurality of circuits which will now be traced and the operation of my invention described.

The main-line conductors + and - are connected by means of conductors 11 and 12 with stationary contacts 22 and 26. A conductor 13 is run from the + main to the pivoted lever 92 of the car-switch. If this car-switch lever is moved to the left onto contact 93, a circuit will be closed through the conductor 95, contacts 60 and 61, which are bridged by plate 58, conductor 97, solenoid winding 87, switch 14 and contact 15, resistance 16 and conductors 17, 39 and 11 to the negative main. The resistance 16 does not allow enough current through the solenoid winding 87 to cause it to raise its core. Consequently, the above operation will not cause the rheostat to be actuated. At the same time, another circuit will be closed at the car-switch through conductor 38, winding 32 of solenoid 30 and conductors 39 and 11. Thus solenoid 30 will be energized and will raise its core. This will cause plates 27 and 28 to be moved up against contacts 21, 22 and 25, 26, respectively, to thereby connect the motor shunt field across the line, and to also close a circuit between the motor armature and the mains through the resistance 81. This operation may also actuate the reversing switch 40 to cause the current to pass through the armature in the desired direction. This forms no part of the present invention, and as it is fully set forth and described in Patent Number 851,933 issued to Howard F. Gurney April 30th,

1907, a specific description of its operation is not deemed necessary. The core 31 will at the same time release the brake 70. The effect of these operations will be to cause the motor to run slowly in one direction and the car 90 to be driven thereby.

When the brake-shoes have been moved away from the brake-pulley, the contact plate 74 will be moved back against stationary contacts 75 and 76. This will short-circuit the resistance 16 so that the current passing from the positive main through solenoid winding 87 will pass directly through contact 15, switch 14, conductor 18, contacts 75 and 76 which are bridged by contact plate 74, and conductors 19, 17, 39 and 11 to the negative main. Solenoid 87 will now receive sufficient current to cause it to raise its core, and the resistance 81 will be gradually cut out of the motor armature circuit under the action of the dash-pot 89. It is to be noted that this part of the operation does not take place until the brake has been actuated and released.

When the core 86 has been raised far enough to have caused all of the resistance 81 to be cut out of the motor armature circuit, its upper end will have reached such a position that it will cause the switch 14 to be moved away from contact 15 into some such position as that indicated by dotted lines. This will again insert the resistance 16 in the circuit with the solenoid winding 87 and the amount of current which the resistance 16 allows to pass through the solenoid winding 87 will be enough to cause the latter to maintain its core in its raised position so that the brushes 82 will remain upon the upper contact 84 while the circuits remain in this condition, and the solenoid winding 87 will not become overheated because its current is cut down by the resistance 16.

The motor and car will continue to run in one direction until the circuit through solenoid windings 32 and 67 is broken, either by some of the automatic arrangements usually employed with apparatus of this kind, or by the operator in the car bringing the car-switch back to its central position. This will cause the current to be cut off from the motor and the brake to be applied. At the same time the brushes 82 will drop and will thereby quickly connect a part of the resistance 81 in series with the motor armature. If the operator throws pivoted lever 92 of the car-switch to the right against contact 94, the operation will be similar to that above described, except that in this case the solenoid winding 57 will be energized and the reversing switch 40 will cause the current to pass through the motor armature in the opposite direction so that the rotation of the motor and the movement of the car will be in the opposite direction to that before mentioned.

I usually employ a single circuit closer as

sociated with the brake for controlling the resistance in the rheostat solenoid-circuit in the manner which I have above described. If, however, it is desired to make the action 5 of the solenoid 87 dependent upon the actuation of both of the brake-levers 93, the parts may be arranged in some such manner as that illustrated in Fig. 2. In this case another contact plate 77 is connected with the 10 other brake-lever and arranged to coact with two stationary contacts 78 and 79 when the brake is released in the manner above described. The conductor 17, which is connected with one end of resistance 16 as before, is also connected with the stationary 15 contact 79. The stationary contacts 75 and 78 are connected together and the stationary contact 76 is connected as before by conductor 18 with the switch 14.

20 The operation of this modification is obvious, for, when the brake has been actuated, contact plates 74 and 77, abutting against stationary contacts 75, 76 and 78, 79, respectively, will short-circuit the resistance 25 16 and allow enough current to pass through solenoid winding 87 to cause the latter to raise its core 86.

The advantages of this invention are obvious. It fully insures the proper rotation 30 of steps in the operation of the controller; it prevents an overload on the motor which might be caused by making the latter work against an applied brake; and it also supplies a time element, during which the motor 35 begins its rotation before its series-starting-resistance is cut out, which time may be augmented by the dash-pot 35. As the resistance 16 is thrown into series with solenoid 87—after it has performed its function of 40 cutting out the starting resistance—it will effect the saving of current and prevent overheating of the solenoid winding 87.

The apparatus shown and described has been arbitrarily selected to illustrate this 45 invention. It is no part of the invention, nor is the general wiring system which I have shown, but the invention may be applied as well to other forms of apparatus and in conjunction with other elevator con-

50 trollers.

Instead of connecting the solenoid winding 87 with the mains through the car-switch, its conductor 97 may be connected with stationary contact 25, and the conductor 17 connected with the stationary contact 21 so that the closing of the starting switch 55 serves to complete its circuit through the resistance 16, which is short-circuited by the releasing of the brake in the manner previously described. This arrangement is 60 shown in Fig. 3.

What I claim is:—

1. In an elevator, a motor, a retarding element therefor, electromagnetic means for 65 moving said retarding element, a resistance

in circuit with said electromagnetic means, and a brake for the motor arranged to cut the resistance out of said circuit.

2. In an elevator, an electric motor, a starting resistance therefor, a solenoid for 70 cutting out the starting resistance, a resistance in circuit with the solenoid, a brake, and means actuated by the brake for cutting the resistance out of the solenoid circuit.

3. In an elevator, an electric motor, a 75 starting resistance therefor, a solenoid for cutting out the starting resistance, a circuit for the solenoid, a resistance for the solenoid circuit, a brake, and means actuated by the releasing of the brake for short-circuiting 80 the resistance in the solenoid circuit.

4. In an elevator, an electric motor, a starting resistance therefor, a solenoid for cutting out the starting resistance, a circuit for the solenoid, a resistance for the solenoid 85 circuit, a brake, a brake-lever, a circuit-closer connected with the brake-lever and arranged to short-circuit the resistance in the solenoid circuit when the brake lever has been actuated to release the brake. 90

5. In an elevator, an electric motor, a starting resistance therefor, a solenoid for 95 cutting out the starting resistance, a circuit for the solenoid, a resistance in the solenoid circuit, a brake, a magnet arranged to actuate the brake, a switch for closing the circuits through said solenoid and brake magnet, and a circuit-closer actuated by the movement of the brake for short-circuiting the resistance in the solenoid circuit. 100

6. In an elevator, an electric motor, a starting resistance therefor, a solenoid for cutting out the starting resistance, a circuit for the solenoid, a resistance in the solenoid circuit, a brake, a magnet arranged to actuate the brake, a switch for closing the circuits through said solenoid and brake magnet, means actuated by the releasing movement of the brake for cutting said solenoid 105 resistance out of the solenoid circuit, and automatic means for again inserting said resistance in the solenoid circuit after said solenoid has been actuated to cut out the starting resistance. 110

7. In an electrically controlled elevator, 115 an electric motor having an armature, a starting resistance in circuit with the armature, a solenoid for gradually cutting out the starting resistance, a starting switch, a brake, an electroresponsive device for actuating the 120 starting switch and the brake, a resistance in circuit with said solenoid, a switch for closing said circuits through the solenoid and the electroresponsive device, and means actuated by the releasing movement of the 125 brake for cutting said resistance out of the solenoid circuit.

8. In an electrically controlled elevator, a car, an electric motor having an armature, a starting resistance in circuit with the armature. 130

ture, a solenoid arranged to cut the starting resistance out of circuit with the motor armature step by step, a dash-pot controlling the action of the solenoid in one direction, a resistance in circuit with said solenoid, a motor starting switch, a brake, a pivoted brake lever connected therewith, an electroresponsive device for actuating the starting switch and the brake lever, a manually operated switch in the car for closing the circuits through said solenoid and electroresponsive device, a circuit-closer connected with the brake lever arranged to short-circuit the re-

sistance in the solenoid circuit when the brake lever has been actuated to release the brake, and automatic means for again inserting said resistance in the solenoid circuit after the latter has been actuated to cut out the starting resistance.

In testimony whereof I have signed my name to this specification in the presence of two subscribing witnesses.

WILLIAM M. CUMMISKEY.
